IGNITION CONTROLLING DEVICE FOR
INTERNAL COMBUSTION ENGINESManuel H. Elkin, Elmira Heights, N. Y., assignor
to Bendix Aviation Corporation, South Bend,
Ind., a corporation of Delaware

Application September 11, 1940, Serial No. 356,321

4 Claims. (Cl. 74—472)

The present invention relates to an ignition controlling device for internal combustion engines and more particularly a device for momentarily grounding the ignition circuit of an internal combustion engine in order to facilitate the shifting of an automatic variable speed transmission operated thereby. The present invention is a species of thermostatic control which is claimed generically in my companion application Serial Number 344,928, filed July 11, 1940.

It is an object of the present invention to provide a novel ignition controlling device which is reliable and efficient in operation while being simple and economical in construction.

Further objects and advantages will be apparent from the following description taken in connection with the accompanying drawing which illustrates semi-diagrammatically a power plant embodying a preferred form of the present invention.

In the drawing there is indicated in dotted lines at 1 an internal combustion engine of conventional form provided with a clutch housing 2 and a variable speed transmission 3 actuated by the engine. Automatic means for shifting the variable speed transmission 3 is provided in the form of a shifter 4 having a shift rail 5 adapted to engage a shift arm 6, longitudinal movement of which controls the speed ratio of the gears in the transmission 3. The shifter 4 is operated in any preferred manner as by means of fluid pressure from the engine and is controlled by any suitable device responsive to speed of the car in which the power plant is located, the load on the transmission, or any other desired function or combination of functions of the vehicle. Since the transmission and its automatic control form no part of the present invention, further description thereof is deemed unnecessary.

The engine 1 is provided with an ignition system comprising a battery 7 which is connected by an ignition switch 8 to the primary of an ignition coil 9, the opposite terminal 11 of which is grounded in the usual manner through a breaker mechanism 12 operated by the engine.

The shifting of the transmission 3 is facilitated by removing the engine load from the transmission during the instant of shifting. As here shown, this is accomplished by providing a grounding circuit comprising a lead 13 connected to the terminal 11 of the ignition coil and to a contact 14 of a grounding switch indicated generally by numeral 15. Switch 15 comprises a second contact 16 connected by a lead 17 through a thermally sensitive resistor 18 to the ground

at 19. Switch 15 is provided with a bridging contact 21 normally out of engagement with contacts 14 and 16 mounted on a sliding plunger 22 normally resting in a notch 23 in the shift rail 5. A second notch 24 is provided in the rail 5 corresponding to the shifted position of the rail, and it will be understood that there are as many notches in the rail as there are operative positions of the variable speed transmission. The resistor 18 is of that type which when cold has a comparatively low resistance, but when heated has a high resistance. Ordinary incandescent lamp filaments have to a greater or less extent such characteristics, so that it is merely necessary to choose a lamp having a filament whose resistance when cold is low enough to effectually ground the ignition system and render it inoperative, while its resistance when hot is such as to cut down the current flowing there-through to an amount so small as not to adversely affect the operation of the ignition system. Various types of ballast tubes also possess the desired characteristics, and by the selection of a suitable lamp or tube, it has been found readily possible to obtain the desired operation of the device while varying the time required to heat the filament and therefore the time during which the ignition is inoperative, to suit the requirements of various types of transmission.

In operation, starting with the parts in the positions illustrated, with the engine in operation the ignition circuit functions in the usual manner since the grounding circuit is opened at the grounding switch 15. When the transmission 3 is to be shifted, the shift rail 5 moves to the right to engage the shift arm 6, and during the initial movement of the shift rail, the switch 15 is closed thereby, thus completing the grounding circuit through the lamp 18, the filament of which is cold and accordingly forms a low resistance connection to the ground. If shifting takes place as usual in a fraction of a second, the shift rail moves to line up the notch 24 with the plunger 22 of the grounding switch 15, whereupon the grounding switch is opened and the operation of the engine is restored. If for any reason, the shifting operation is interrupted at an intermediate point, the ground switch 15 will be maintained closed by the shift rail 5. In such case, however, the current flowing from the ignition circuit through the grounding circuit heats the filament of the resistor 18 whereby its resistance rises to such a value that the operative condition of the engine ignition is restored in spite

of the fact that the grounding switch 15 remains closed. The engine, therefore, continues to operate until proper measures are taken to secure proper operation of the automatic shifting means. When this is done, switch 15 opens since the shift rail has then moved to one of its operative positions and the resistor 18 immediately cools off and is ready for the next cycle of operation.

Although but one form of the invention has been shown and described in detail, it will be understood that other forms are possible and various changes may be made in the design and arrangement of the parts without departing from the spirit of the invention as defined in the claims appended hereto.

What is claimed is:

1. In combination with an internal combustion engine having an ignition system, a grounding circuit for the ignition system including a switch and a resistor in the form of a metallic filament in an inert atmosphere, and means for closing the switch, the resistance of the filament when cold being so low as to render the engine ignition inoperative when the switch is initially closed, and the resistance of the filament when heated by current of proper voltage passing therethrough being so high as to prevent the grounding circuit from interfering with the operation of the engine ignition.
2. In combination with an internal combustion engine having an ignition system, a variable speed transmission driven thereby, and means for automatically shifting the transmission, a grounding circuit for the engine ignition including a normally open switch and a non-inductive resistor having a positive temperature coefficient,

and means for closing said switch during the shifting of the transmission, the resistance of the resistor when cold being so low as to render the engine ignition inoperative, and the resistance when heated by the current passing therethrough from the ignition circuit being so high as to prevent the grounding circuit from adversely affecting the operation of the ignition circuit.

3. In combination with an internal combustion engine having an ignition system, a variable speed transmission driven thereby, and means for automatically shifting the transmission, a grounding circuit for the engine ignition including a normally open switch and an incandescent lamp, the resistance of the lamp when cold being so low as to render the engine ignition inoperative, and the resistance of the lamp when lit being of such value that the ignition is rendered operative irrespective of closure of the grounding switch.
4. In combination with an internal combustion engine having an ignition system, a variable speed transmission driven thereby, and means for automatically shifting the transmission, a grounding circuit for the engine ignition including a normally open switch and an incandescent lamp, the resistance of the lamp when cold being so low as to render the engine ignition inoperative, and the resistance of the lamp when heated by passage of the current therethrough from the ignition circuit for a predetermined time, being so high as to insure proper operation of the engine ignition irrespective of closure of the grounding circuit.

MANUEL H. ELKIN.
